PLANNING BOARDS

Theodore B. Parker, Hamilton, and Robert G. Willard,
Cincinnati, Ohio

Application November 2, 1955, Serial No. 544,474

3 Claims. (Cl. 40—63)

The invention relates to means particularly adapted for planning the production of articles or the performance of services.

The invention is, also, adapted to facilitate in the actual progress of work with a previously established schedule.

An important object of the invention is to enable users and operators to quickly and conveniently attach, remove and relocate cards on other indicia on a chart or board.

Another object of the invention is to provide simple, efficient and practical means to enable users and operators to quickly and conveniently move or slide cards or other indicia transversely and longitudinally of the card holding strips.

Other objects and novel features of the invention will become apparent from the description which follows, taken in connection with the accompanying drawings, in which:

Fig. 1 is a plan elevational view of the chart, with parts broken away;

Fig. 2 is a section taken on line 2—2 in Fig. 1, with parts broken away and showing a card being attached to the chart;

Fig. 3 is the same sectional view showing a card attached to the chart;

Fig. 4 is the same section showing a card being removed from the chart.

Fig. 5 is an enlarged view of a portion of a strip; and

Fig. 6 is a side view of a chart showing a modification of the invention.

In the preferred construction of the invention we provide the display board or chart 1 which in part comprises the foundation panel or support 2 adapted to be hung on a wall or placed in any other position suitable for use.

The panel 2 may be formed from any suitable material as plywood, plastic, metal wood or the like, and of any desired shape or configuration appropriate to the desires of the individual. For convenience and practical usage the panel 2 is illustrated as of substantially rectangular shape. The horizontal top edge 3; the vertical side edges 4 and 5; and the horizontal bottom edge 6 of the panel are so positioned for convenience. Nevertheless the chart may be suspended from a wall, supported by an easel or simply utilized in other respects, as in a filing cabinet, for convenience of the user with either side edge 4 and 5 at the top or uppermost position, the top edge 3 and the bottom edge 6 in vertical or other selected position.

Suitably attached to the front surface 7, of the panel 2, as by nails 8, are the elongated strips or plates 9 whose middle portions 9' are substantially of concavo-convex formation. Preferably the strips or plates 9 are formed of springy, flexible material as metal, plastic, or other suitable material for the purposes hereinafter explained and described. As many strips 9 as desired by the user may be attached to the panel 2 which may be of any size and shape to accommodate the various cards.

The upper edge or side 10, of each strip 9, is substantially flat to conform with the formation of the front surface 7 of the panel 2 in contact with which the flat side rests. The lower edge or side of each strip 9 has a hook or trough-like portion 11 formed thereon. The hook 11 extends the full length of the strip 9 and comprises the rear vertical leg 12 spaced apart from and parallel with the front vertical leg 13 whereby the groove 14 is formed or provided at the lower edge of each strip.

2

A plurality of strips 9 are fastened to the front surface 7 of the panel 1, and with the upper strip 9 overlapping the next adjacent lower strip and with the lower edge of the leg 12 of the hook 11 in contact with the convex outer surface 15 of the concavo-convex middle portion 9' of the strip.

As illustrated particularly in Figs. 1 and 2 the strips 9 are arranged in parallel overlapping relation and with their convex sides 9' disposed forwardly of the panel 2. These strips are retained in stationary or fixed positions, with respect to the panel 2 and with respect to each other, by the nails 8 received through the upper flat edge 10 so that the lower edge of a strip is located forwardly and in substantial contact with or adjacent the convex portion 9' of the next lower strip whereby a plurality of elongated cards or sheets 16 may be manually positioned between the various strips and held under pressure in a selected and predetermined position, as shown in Fig. 1. Also, a rectangular card 16' or a plurality thereof can be manually attached to the chart, as shown in Fig. 1.

The cards or sheets 16 and 16' may be made of paper, plastic or similar material which at least has a relatively moderate coefficient of resilience because it is advantageous, in some respects as hereinafter explained, that the cards have some flexibility and resiliency and will spring back to or near to their original shape after being bent or distorted. Also, the cards may be provided in any desired color or combination of colors when it is desired to give distinctiveness to the display board or chart or enable the operator to quickly and conveniently segregate various sections of the chart. Any desired color scheme, combination or variations may be used such as different colors in each selected area or section. Suitable signs, pictures, letters, words, numerals, or other indicia 17 may be painted, printed or otherwise placed on the front side 17 of each card 16 and 16'. This feature is particularly advantageous when it is considered and realized that the chart 2 has a versatility of uses in a wide variety of applications such as production or development schedules, load charts, bar-graphs, personnel rosters, organization charts, merchandise price lists, directories, indexes, and the like.

An operation of the invention is, as follows: A card 16 whose length may or may not be sufficient to extend the full length of the strips 9 is manually grasped by the person (not shown) or operator. The operator manually forces the upper edge 18 of the card between the hook 11, of one strip, and the concavo-convex portion 15 of the next upper strip until the lower edge 19 of the card is above the upper edge 20 of the leg 13 of the hook 11, as shown in Fig. 2. When sliding the upper edge 18 of the card between the strips the lower edge or hook 11 of the upper plate may be, if desired, manually forced or sprung outwardly from contact with the adjacent convex surface 15. The operator manually forces the lower edge 19 of the card rearwardly toward or in contact with the convex surface 15, of the adjacent strip after which the operator, by manual contact with the outer surface of the card 16, forces or slides the card downwardly until its lower edge 19 is received in the groove 14, as shown in Fig. 3, whereby the upper edge 18 of the card is retained in stationary position between the hook 11 of the adjacent and next upper strip 9 and the convex surface 15 of the next lower strip, and the lower edge 19 is in the groove 14 which prevents forward or downward movement of the card.

Advantages of the operator being able to insert the card 16 in stationary position on the panel 2, as above described, is, first, the card is held in a predetermined stationary position independently of other adjacent strips, and irrespective of the length of the particular inserted card; and, second, a relatively short card may be placed

onto the chart 1, and removed therefrom, without disturbing other cards whose lower edge is in the same groove 14 if the cards were manually slid endwise into the grooves 14.

Preferably the shape, location and material of which the strips 9 are formed is such as to provide a slight spring pressure on the portion of a card contacted by the convex surface 15 and the hook 11 of the next lower adjacent strip. Therefore, when the operator desires to remove a card from the chart 1 he, simply with his fingers, forces or slides the card 16 upwardly until its lower edge 19 clears or is above the upper edge of the leg 13, of the hook 11. When the operator removes contact of his fingers on the card the resiliency and flexibility of the card ordinarily will cause the lower edge 19 to move outwardly from the front of the panel 2 and at an angle thereto and to the position or near position shown in Fig. 2, and the operator can conveniently grasp with his fingers the lower edge 19 and manually slide or force the card downwardly causing the upper edge or top of the card to slide from between the contacting hook 11 and the convex slide 15 of the engaged next upper strip.

Sometimes a card may be formed from non-resilient or non-flexible material, or a resilient and flexible card once affixed to the chart may by dampness, wetness or other reasons become non-resilient or lose its flexibility and, therefore, permanently assume the shape of the strip against which it is held while on the chart.

In case the resiliency and flexibility of the card 16 is insufficient to cause its lower portion to spring or move outwardly from the panel 2, as shown in Fig. 2, after the lower edge 19 is slid upwardly and above the top edge of the leg 13, of the hook 11, the lower edge 19 nevertheless will be spaced from the adjacent convex surface 15, as shown in Fig. 4, to enable the operator to conveniently insert a finger or finger nail between the adjacent convex surface 15 and the lower edge 19 of the card, because the lower edge 19 of a non-flexible, non-resilient and non-springy card will be molded to the shape of the outer or front surface of the strip 9 against which it was previously held. Therefore, the lower edge 19 of the card which has been positioned in the groove 14 and between the vertical leg 12 and the vertical front leg 13 will extend at an angle, as shown in Fig. 4, from the outer or front surface of the adjacent strip 9. This is so because the lower half of the convex surface 15 curves upwardly and outwardly or forwardly, whereas the leg 12 is perpendicular and when the card, molded to the front surface of the strip 9, is moved upwardly a short distance the lower end of the leg 12 contacts the lower portion of the convex surface 15 thereby causing the formerly perpendicular or vertical lower edge 19 of the card to protrude or extend forwardly and downwardly from the panel 2 and the adjacent strip 9, as shown in Fig. 4.

The card 16' is inserted on the chart 1 by the same procedure above explained with respect to the card 16, except that the card 16' spans one strip whereby the lower edge of card 16' is received in the hook 11 of the strip whose upper edge is adjacent the hook of the strip having the convex surface which the upper edge of the strip contacts and is retained there against as by the hook of the next upper strip.

Cards or sheets of various heights and lengths can be conveniently attached to and incorporated with the chart 1 as by inserting the top edge of the card or sheet between a hook and the adjacent convex surface of a strip and then manually pulling the card or sheet downwardly to insert its lower edge into the groove of the 70 suitably positioned lower strip.

In Fig. 6 is shown a modification of the invention in which the board 1' has attached thereto the flexible plates 21 each of which has the concavo-convex middle portion 21'. The rear leg 22 of the hook 23 is curved forwardly

and is integrally connected with the lower edge 24 of the concavo-convex middle portion 22. When installing a card or sheet 25 on the chart, the upper edge of the card is slid between the hook 23 and adjacent the convex surface 22, and then the card 25 is slid downwardly with its lower edge positioned in the groove 26, as shown in Fig. 6.

While we believe that the form of the invention illustrated in the drawings and referred to in the above description, as the preferred embodiment, is efficient and practicable yet realizing that the conditions concurrent with the adoption and utilization of our invention will necessarily vary, we desire to emphasize that changes in the details may be resorted to, when required, without sacrificing any of the advantages of the invention, as defined in the claims.

What we claim as new and desire to secure by Letters Patent is:

1. A display board comprising a panel, a strip fastened to the front of said panel and having a middle section with an area on its front and having a lower flat perpendicular section at its bottom and adjacent said area, and having a trough like means integral with said flat perpendicular section to receive the lower edge of a card, means forwardly of said strip and said panel in contact with said card to releasably hold said card under pressure whereby said card can be manually moved upwardly to remove the lower edge of said card from said trough like means, said convex area adapted to force the lower edge of said card forwardly from contact with said strip to enable an operator to conveniently grasp the lower edge of said card with his fingers to pull the card from between said strip and said first mentioned means.
2. A planning board for releasably holding a flexible springy card, and comprising a vertical panel, a strip fastened at its top to the front of said panel and having a middle section with a convex area on its front and having a lower flat perpendicular section at its bottom and adjacent said convex area, and having a trough like means integral with said lower flat perpendicular section to receive the lower edge of said card, springy means intermediate said strip and said panel in springy contact with said strip to releasably hold said card in contact with said convex area whereby said card can be manually moved upwardly between said strip and said springy means to remove the lower edge of said card from said trough like means and allow the lower edge of said card to spring forwardly from contact with said strip to enable an operator to grasp the lower edge of said card with his fingers and pull the card downwardly from between said strip and said first mentioned means.
3. A planning board for releasably holding a card, and comprising a vertical panel, a strip fastened at its top to the front of said panel and having a middle section with a convex area and having a lower section at its bottom and adjacent said convex area, and having a trough like means integral with said lower section to receive the lower edge of said card, springy means intermediate a portion of said strip and said panel and in springy contact with said strip and adapted to releasably hold said card in contact with said strip.
